[57] CLAIM

The ornamental design for a standing sign, substantially as shown and described.

DESCRIPTION

FIG. 1 is a front perspective view of a sign showing our new design.

FIG. 2 is a front elevational view thereof, the reverse side being identical in appearance thereto.

FIG. 3 is a side elevational view of the embodiment of FIG. 1.

FIG. 4 is a top plan view thereof.

FIG. 1

FIG. 2

FIG. 3

FIG. 4
